UNITED STATES PATENT OFFICE

GEORG VON ARCO, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

MEANS TO KEEP MECHANICAL DRIVING MECHANISMS AT A CONSTANT RATE OF ROTATION

Application filed April 9, 1927, Serial No. 182,516, and in Germany April 15, 1926.

It has previously been suggested to keep the running of clocks and similar mechanical driving means constant by using a device adapted to generate oscillations of very constant frequency, such as tuning fork vibrations, the tuning fork influencing an electric circuit by way of contacts, the latter circuit insuring constancy of rotation of the clock-work. But these devices have failed of attaining practical importance because they comprised electric circuit breakers, at one or more points, of very small motion amplitudes so that extremely exact adjustment was necessary, which, however, could not be maintained for any length of time on account of wear of the contacts.

The object of this invention is to devise means for obtaining constant speed from ordinary driving devices.

Another object of this invention is to keep different driving mechanisms in step.

A further object of the invention is to keep a driving motor in step with an oscillatory circuit.

A still further object of the invention is to obviate electrical contact devices in constant speed apparatus.

Further objects of the invention will be apparent from the following specification and drawings in which:

The single figure represents schematically an embodiment of the invention.

In said drawing, 1 represents a driving motor of any suitable type either electrical or mechanical.

Coupled therewith through the medium of gears 2—3 is the wheel 4 of a La Cour wheel device. Said wheel 4 is in its usual form a fine-toothed wheel constructed of magnetic material for instance iron. In the so-called La Cour wheel, the fine-toothed wheel is subject to the action of electro-magnetic devices fed with alternating currents in any suitable manner.

In the present instance, 5 represents schematically the coil in the output circuit of a thermionic generator and amplifying apparatus 6.

Another plan would be to supply the La

to the oscillatory field so that in reality the wheel 4 would be affected by a pulsating constant field.

As is evident from the drawing the mechanical driving mechanism is so geared, that with the La Cour wheel coupled therewith mechanically, and without outside assistance the two will run in rather close synchronism with the generated alternating current of the thermionic oscillator. The mechanical power therefore can be said to consist of two parts, in the main of the mechanical energy source 1 and in a minor degree of the electrical source 4—5. Thus if the mechanical source should show a tendency to speed up for any reason this is prevented from occurring by the electric brake. When however the mechanical driving mechanism tends to slow up the electrical end will supply a supplementary torque sufficient to boost the speed of the motor to the required level.

Of course any suitable utilizing device could be connected up with the motor shaft in any well known manner.

It is thus evident that by means of this invention a very simple and highly efficient speed control means may be had for comparatively small driving means.

Having thus described my invention, what I claim as new and desire to protect by Letters Patent is:

1. In a constant speed device, a driving mechanism, a synchronous motor device having a fine toothed wheel, step-up mechanism for connecting said driving mechanism to said fine toothed wheel, a local thermionic oscillation generator adapted to generate oscillation of a constant frequency and means controlled thereby and acting on said fine toothed wheel for maintaining the speed of said driving mechanism constant.

2. In a constant speed device a driving unit, an auxiliary unit mechanically coupled thereto, both of said units being coupled to a driven element, said auxiliary unit being adapted to rotate a greater number of times per unit of time than said driving unit, a constant frequency thermionic oscillation generator and means controlled by the energy generated therein and acting on said

auxiliary unit for maintaining the speed of said driving unit constant.

3. In a constant speed device, an electronic generator, a main driving unit and an auxiliary unit said last named unit comprising a La Cour wheel, a speed reducing means for connecting said La Cour wheel to said main driving unit and means controlled by the frequency of the energy generated in said electronic generator for maintaining the speed of said driving unit approximately constant.
